[57] CLAIM

The ornamental design for an actuator for pump dispenser
for lotion or the like, as shown and described.

DESCRIPTION

FIG. 1 is a perspective view showing my new design with
the pump collar in broken lines for illustrative purposes only
and forming no part of the claimed design.

FIG. 2 is a top plan view;

FIG. 3 is a right side elevation;

FIG. 4 is a front elevation;

FIG. 5 is a rear elevation; and,

FIG. 6 is a bottom plan view.

The left side elevation is a mirror image of the right side
elevation.
